The ornamental design for a furniture light assembly, as shown and described.

DESCRIPTION

FIG. 1 is a left, front perspective view of a furniture light assembly mounted on a sofa, according to an embodiment of the invention, wherein a right, front perspective view (not shown) is a mirror image thereof;

FIG. 2 is a front view of the furniture light assembly of FIG. 1;

FIG. 3 is a rear view of the furniture light assembly of FIG. 1; FIG. 4 is a left side view of the furniture light assembly of FIG. 1, wherein a right side view (not shown) is a mirror image thereof;

FIG. 5 is a top view of the furniture light assembly of FIG. 1; and,

FIG. 6 is a bottom view of the furniture light assembly of FIG. 1.

The dashed lines in FIGS. 1 through 6 represent features of a sofa and portions of the light assembly which do not form part of the claimed design.

The Stipple Pattern applied to the drawings represents surface shading.
